FRANZ LANG, OF MUNICH-NYMPHENBURG, GERMANY, ASSIGNEE TO ACRO AKTIEN-
GESELLSCHAFT, OF KÜSSNACHT AM RIGI, SWITZERLAND

OIL MOTOR

Application filed February 11, 1927, Serial No. 187,529, and in Germany February 19, 1926.

This invention relates to an oil motor provided with a hollow space in the piston, serving as additional compression space, as disclosed in my copending application Serial No. 5 28,899.

In order to avoid the necessity of elongating the piston for the accommodation of the hollow space as slightly as possible, said hollow space is made annular according to the 10 present invention, whereby at the same time the advantage is obtained, that the additional compression space is not disposed directly above the point of attachment of the piston rod. Moreover between said point of attachment and the additional combustion space a higher stratum of air is present which insulates said point of attachment against the heat radiation of the additional compression space.

20 In the accompanying drawing, illustrating the subject matter of the invention by way of example,

Fig. 1 shows the upper part of a cylinder in longitudinal section,

25 Fig. 2 is a cross section on the line $\alpha-\alpha$ of Fig. 1.

Fig. 3 shows a modification in longitudinal section and

30 Fig. 4 is a cross section on the line $y-y$ of Fig. 3.

In the drawing the reference character a indicates the cylinder, b the piston and c the additional compression space provided within said piston. This additional compression space has an annular shape and its cross section is reduced in upward direction, so that a slit d is formed, which also has annular shape and connects the space c with the primary combustion space e of the cylinder. 35 The annular slit or channel d is funnel-like enlarged in front of the reduction or throttling restriction in order to favor the mixing of the fuel with the air. The fuel nozzle f is disposed in the center of the cylinder head 40 and arranged in such a manner that the fuel passes in the shape of a conical mantle or veil and in uniform distribution toward the annular channel d of the additional compression space. The injection can be effected with 45 or without compressed air. Suitably, the nozzle

5 zle f is made vertically adjustable in its central axis, in order to adjust said nozzle in accordance with the position of the piston, corresponding to the moment of injection in such a manner, that the jets of fuel are safely guided toward the annular channel d . As may be seen from Fig. 1 a high air space i is provided above the point of attachment of the piston rod, so that said point of attachment is protected against the head radiation. 60 of the additional combustion space c . The operation of the present engine is substantially the same as the operation of the engine disclosed in my copending application Serial No. 28,899.

65 In order to enable a still further shortening of the piston, a further additional compression space g is arranged within the annular space c in the modification illustrated in Figs. 3 and 4, said further additional compression space g being connected with the compression and combustion space i of the cylinder by means of a reduced aperture or throttling restriction h . In this case the nozzle f has a further bore, arranged in the central axis of the needle and adapted to inject fuel toward the space g .

70 If desired, the additional compression space can be formed as a special body inserted into the piston, which inserted body can be easily exchanged. Instead of the annular channel g several funnel-shaped openings arranged in a circle can connect the two compression spaces.

75 In the illustrated forms of construction the motor is disclosed as a two-cycle motor, that means the feeding of the air and the discharge of the combustion gases are regulated by the piston by means of slots. The invention of course can be applied also to all engines in which separate regulated valves for the feeding of air and the exhaust of the combustion gases are required; of these engines the four-cycle engines are the most common.

80 I claim:

1. A combustion engine with self-ignition, comprising a cylinder and a piston reciprocating therein, said piston being provided with an annular compression space arranged therewithin and connected by a ring-shaped 85

aperture of reduced cross-section with the compression space of the cylinder.

2. A combustion engine with self-ignition, comprising a cylinder and a piston reciprocating therein, said piston being provided with an annular compression space arranged therewithin and connected by a ring-shaped aperture of reduced cross-section with the compression space of the cylinder, said ring-shaped aperture having a funnel-like enlargement opening outwardly.

3. A combustion engine with self-ignition, comprising a cylinder and a piston reciprocating therein, said piston being provided with an annular compression space arranged therewithin and a central hollow space, both spaces being connected in the same manner with the compression space of the cylinder.

4. A combustion engine with self-ignition comprising a cylinder, a piston reciprocating therein, said piston being provided with an annular compression space arranged therewithin and connected with the compression space of the cylinder, and a fuel nozzle arranged in the cylinder head and being vertically adjustable on its central axis in order to adjust the distance of the nozzle from the inlet opening of said annular compression space.

30 In testimony whereof I have hereunto affixed my signature.

FRANZ LANG.
